UNITED STATES PATENT OFFICE

2,574,660

MECHANICAL COIN WRAPPER

Earl H. Roberts, RAVENA, N. Y.

Application September 2, 1947, Serial No. 771,784

8 Claims. (Cl. 93—2)

1

This invention relates to new and useful improvements in mechanical coin wrappers and the primary object of the present invention is to provide a device for the reception of a selected amount of similar coins and including novel and improved means for quickly and readily placing a wrapper about the coins to retain the same in a small, compact package.

Another important object of the present invention is to provide a mechanical coin wrapper including novel and improved means for conveniently tightening a wrapper about a stack of similar coins that are inserted in the device.

A further object of the present invention is to provide a coin wrapper including novel and improved means for guiding a wrapper to be spirally wound about a stack of coins.

A still further aim of the present invention is to provide a coin wrapper that is simple and practical in construction, strong and reliable in use, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the present invention showing the wrapper partially rolled within the tubular body;

Figure 2 is a side elevational view of Figure 1, and with parts thereof broken away and showing sections;

Figure 3 is an enlarged transverse vertical sectional view taken substantially on the plane of the section lines 3—3 of Figure 1;

Figure 4 is an enlarged longitudinal vertical sectional view of the actuating mechanism and guide supporting the same, and with dotted lines showing the position of the actuating mechanism when it is desirable to remove the package of coins from the device; and,

Figure 5 is a plan view of the wrapper used in conjunction with the present invention.

Referring now to the drawings in detail, wherein for the purpose of illustration, there is disclosed a preferred embodiment of the present invention, the numeral 10 represents a tubular body having a longitudinal slot 12 in one side. Slidably and rotatably mounted in one end of the body, is an actuating rod 14 having a substantially frusto conical finger gripping portion

2

16 at one terminal. Removably secured on the opposite terminal of the rod 14, is a retaining plug 18 having a central recessed portion 20 that receives a nut 22 threadingly engaged on rod 14.

5 Also removably secured on rod 14, is a beveled plug 24, preferably of a resilient material, having its reduced face bearing against one face of plug 18.

An angle iron guide and supporting member 26 having its longer preferably concavo-convexed leg 28 rigidly secured by suitable means to the outer periphery of the body 10, is provided with an aperture 30 in its shorter leg 32 that slidably and rotatably engages rod 14. A coil spring 33 loosely mounted on rod 14 is biased between the annular hub portion 34 of plug 24 and the inner face of leg 32, to normally retain plug 18 and 20 within the body 10 at one end. Preferably, a substantially frusto conical washer 36 carried by the outer face of leg 32 about aperture 30, limits the movement of rod 14 relative to the guide 26 in one direction.

A longitudinal guide bar 38 which is spaced parallel to one edge of slot 12, has its ends turned outwardly and these legs are rigidly secured to the body 10 by any suitable means. The opposite edge 40 of the slot is turned outwardly for a purpose which will later be more fully described.

30 In practical use of the device, a plurality of similar coins are placed into the open end of the body 10 to form a stack supported by the retaining plug 18. The shorter edge of a substantially trapezoidal wrapper 42 is inserted between guides 38 and one edge of the slot 12 to pass about the inner periphery of the tubular body and to be spirally wound about the stack of coins within the body. It should be here noted, that the diameter of the retaining plug

35 18 is slightly smaller than the diameter of the coins, that the diameter of the plug 24, at its larger portion, is greater than the diameter of the coins, and that the diameter of the body 10 is slightly greater than the diameter of the coins plus the wrapper wound thereabout. Further, the shorter parallel edge of the wrapper is also wound about the plug 24 during its winding about the coins. By pressing inwardly upon the end of the body adjacent plug 24, the wrapper will be pressed tightly against the plug 24 so that when the knob 16 is turned in a counter clockwise direction, the plug 24, which is slightly larger than the diameter of the coins, will frictionally bear 40 50 55 against the inner periphery of the wound wrap-

per to tighten the same about the coins embraced thereby.

To release the plug 24 from engagement with the wrapper, it is merely necessary to rotate rod 14 in a clockwise direction slightly, and pull knob 16 of the guide 26 outwardly from body 10 whereby coil spring 33 will be compressed to extend rod 14 and plug 24 outwardly, and package of coins thus loosened may then be removed from the open end of body 10, and the ends then sealed by hand.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A coin wrapping machine comprising a resilient tubular body having a longitudinal slot in one side throughout the length thereof and adapted to be compressed, a member slidably and rotatably mounted in one end of said body, means yieldingly urging said member into said body, means for guiding the movement of said member relative to said body, a retaining plug carried by said member for normally supporting a stack of coins inserted in the opposite end of said body from said member, means for guiding the insertion of wrapper in the slot in said body, means carried by said member for tightening a wrapper about a stack of coins in the body as the body is compressed.

2. The combination of claim 1 wherein said means for guiding the movement of a wrapper about the stack of coins includes a longitudinal guide member spaced parallel to one edge of said slot.

3. The combination of claim 1 wherein said means for guiding the movement of said wrapper about the stack of coins includes a longitudinal guide spaced parallel to one edge of said slot, the terminals of said guide being turned outwardly and secured to said body, and the opposite edge of said slot being turned outwardly.

4. The combination of claim 1 wherein said means for guiding the movement of said member includes an angle member having one leg rigidly secured to the outer periphery of said body.

5. The combination of claim 1 wherein said means for tightening a wrapper about a stack of coins as the body is compressed includes a beveled plug carried by said member adjacent said retaining plug, said beveled plug adapted to engage one edge of a wrapper.

6. The combination of claim 5 wherein said beveled plug is of a resilient material.

7. A coin wrapping machine comprising a tubular body of resilient material having a longitudinal slot in one side throughout the length of said body, a rod slidably and rotatably mounted in one end of said body, a retaining plug carried by one end of said body engaging a stack of coins inserted in the opposite end of said body from said rod, a beveled plug carried by said rod adjacent said retaining plug, an angle guide having one leg rigidly secured to the outer periphery of said body, the opposite leg of said guide having an aperture slidably receiving said rod, a spring mounted on said rod and biased between said angle member and said beveled plug for normally retaining said plugs within said body, a longitudinal guide spaced parallel to one edge of said slot for engaging one edge of a wrapper, the opposite edge of said slot being turned outwardly for the reception of a wrapper extended through said guide, said beveled plug adapted to engage one edge of a wrapper disposed in said body, and means for rotating said beveled plug to tighten a wrapper about a stack of coins as an external, compressive force is applied to one end of said body, said plugs being disengaged from a wrapper and coins upon outward movement of said rod relative to said body.

8. A coin wrapping machine comprising an elongated tube of resilient material split throughout its length, a beveled plug slidably and rotatably mounted in one end of said tube for rolling and tightening a wrapper in the tube about coins in the tube as the tube is manually compressed to force one end of the wrapper against the periphery of the plug, and means yieldingly urging said plug into said tube.
